UNITED STATES PATENT OFFICE

2,657,051

COMBINED GUIDE AND TABLE STRUCTURE

Harry J. Waechter, Mount Healthy, Ohio, assignor to Paul Benninghofen and F. B. Diesbach, Hamilton, Ohio, trustees

Application August 12, 1947, Serial No. 768,106

1 Claim. (Cl. 271—59)

1

This invention relates to guiding apparatus and is particularly directed to a combined table and guide construction for use in guiding strips of paper as they are fed across the top of the table. The guide means of this invention has ready application to use in autographic registers wherein the guides maintain strips of paper for uniform guiding movement along the writing platen as they are fed through the register. In the past, structures of this general character have involved parts which were rather complex and extended, were in the way, and were difficult to adjust or to remove. Adjustment has usually required the loosening of screws and the alignment of parts.

It has been the object of the present inventor to provide an adjustable guide element which can be quickly applied to an edge of the writing platen or the table and which can be readily moved in and out to any desired adjusted position through the simple procedure of gripping the guide element in such manner as to detach its securing means and to quickly move it to the desired position.

It has been a further object of the present inventor to provide a guide of this nature which can be applied to the table structure without a great deal of structural modification of the table. It is only necessary to provide grooves in the table surface in order to provide the necessary component attachment or locking means in the table.

It has been a still further object to provide adjustment guides which are of clip form and which can be readily manufactured from a single piece of metal by blanking out the metal and bending it to constitute the component members.

It has been a still further object of the present inventor to provide guides in which there is an inherent spring tension for holding them in the desired adjusted positions.

It has been a still further object to provide guides of this character which can be completely removed from the register in a matter of seconds so that if the user does not desire to have the guides on the machine they can be completely removed without destroying the appearance of the register or the structure.

Other objects and certain advantages will be more fully apparent from a description of the drawings in which:

Figure 1 is a fragmentary perspective view of a portion of a table or platen showing the guides of the present invention incorporated therein.

Figure 2 is a sectional view taken on line 2—2,

2

Figure 1, illustrating, in detail, one of the guides in position.

Figure 3 is a sectional view taken on line 3—3, Figure 2.

5 The guide of this invention, as stated, may be employed for a number of uses. It is shown herein applied to the edge or edges of a table structure such as the writing platen of an autographic register for the purpose of guiding paper along the platen. The guide and table structure are designed so as to permit adjustment of the guides to accommodate various widths of paper. In the form shown, the guides are mounted at opposite edges of the guide table or platen. The 10 table structure 9 as provided in this form includes inwardly extending notches or slots 10 at its opposite edges, these slots being directly opposite, that is in alignment crosswise of the table in the preferred form. In the form illustrated, which is the casing structure of an autographic register, the sides of the register include openings generally indicated at 11, the slots projecting inwardly from the upper edges of these openings. The slots may be made of any depth 15 desired depending upon the amount of adjustment required.

20 Grooves 12 are provided along the top of the table longitudinally thereof. These grooves are interrupted by the slots 10 themselves, that is to say aligned portions of the grooves are present at either side of the slots. The grooves are spaced laterally with respect to the table and provide for fairly close adjustment of the guides. The 25 grooves constitute the means on the table for securing the guides in adjusted positions and they are therefore of the correct length to accommodate the full width of the guide members which engage them. In the instance shown there are three grooves utilized and it will be 30 desired that the number of grooves may be varied at will.

35 The guides are in the form of clip brackets, being generally indicated at 13. Generally speaking, in each instance they include an upper guide flange 14, an outer or back guide wall 15, spring clip portions 16 and detent edges 17 for engaging the respective grooves 12.

40 Each clip is made up of a single piece of metal appropriately cut and bent to provide the guide and attaching portions. The flanges 14 in each case are disposed horizontally with respect to the platen when the guides are in working position. The outer or back walls 15 are disposed vertically and prevent outward or sidewise displacement of the sheets being guided. From the 45

intermediate portion of the outer guide wall 15 each guide includes a loop section 18 terminating at its lower end in a substantially horizontally disposed spring member 19. This spring member 19 is curved at its outer end and engages the underside of the table or platen 9. That portion of the guide, namely the loop portion which is disposed within the slot 10 is reduced in width so as to fit within the slot 10. The spring arms are the full width of the guide. This notching out or narrowing of the width of the guide makes it possible to provide the downwardly disposed slot engaging edges or detent edges 17 at either side of the slot 10. As shown in Figure 2, these edges 17 fit within the grooves, being held therein by virtue of the inherent spring pressure applied through the spring arms.

When it is desired to change the position of the guide, the operator merely lifts the upper portion of the guide, namely the upper guide flange, thus raising the locking edges from the groove in which they are disposed permitting inward or outward sliding motion of the guide whereby it may be locked again in relation to another one of the grooves.

Thus it will be apparent that a very efficient guide means is provided which will be effective for preventing lateral shifting of the paper and will prevent upward displacement under normal conditions. The guides will remain firmly in position because of the inherent spring tension and are not readily displaced from position unless the operator desires to remove them. The guides can be completely removed from the table if desired by sliding them outwardly to the outer ends of the slots 10.

Having described my invention, I claim:

The combination of a table for an autographic register or the like and an adjustable guide unit for guiding strips of paper longitudinally of said table, said guide unit formed from a single piece of resilient sheet metal and comprising a vertical

wall, a horizontal flange extending from the upper end of said wall, said table having a lateral slot extending inwardly from one side edge thereof, said slot being substantially narrower than the longitudinal extent of said vertical wall, a plurality of grooves extending longitudinally of the table from opposite sides of said slot, a spring arm extending substantially parallel with said horizontal flange, said arm being wider than said slot and adapted to engage the underside of said table and thereby bias said vertical wall downwardly against the top of said table, said spring arm joined to the back wall by a connecting portion of reduced width adapted to fit into said slot, and the lower edges of the vertical back wall at the two sides of the connecting portion constituting groove engaging edges engageable in said grooves under the bias of said spring arm to lock the guide unit against displacement laterally with respect to said table.

HARRY J. WAECHTER.
